UNITED STATES PATENT OFFICE.

JOHN D. BLAKE, OF ROCK ISLAND, ILLINOIS, ASSIGNOR TO BLAKE SPECIALTY COMPANY, OF ROCK ISLAND, ILLINOIS, A CORPORATION OF ILLINOIS.

DESIGN FOR A STREET-LAMP.

45,785.

Specification for Design.

Patented May 19, 1914.

Application filed March 7, 1914. Serial No. 823,264. Term of patent 7 years.

To all whom it may concern:

Be it known that I, JOHN D. BLAKE, a citizen of the United States of America, residing at Rock Island, in the county of Rock Island and State of Illinois, have invented a new, original, and ornamental Design for Street-Lamps, of which the following is a specification, reference being had to the accompanying drawing, forming part thereof.

The figure is a front elevation of a street lamp, showing my new design.

I claim:

The ornamental design for a street lamp, as shown.

JOHN D. BLAKE.
